(57) **CLAIM**

The ornamental design for a food storage container, as shown and described.

DESCRIPTION

FIG. 1 is a perspective view of a food storage container in an open configuration, showing my new design;

FIG. 2 is a perspective view of the food storage container in a partially closed configuration;

FIG. 3 is a perspective view of the food storage container in a closed configuration;

FIG. 4 is a front elevational view of the food storage container of FIG. 1;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is another perspective view of the food storage container shown in FIG. 2;

FIG. 11 is another top view of the food storage container shown in FIG. 8; and,

FIG. 12 is another perspective view of the food storage container shown in FIG. 3.

The broken lines depict portions of the article that form no part of the claimed design.

1 Claim, 9 Drawing Sheets
